DESIGN FOR A HANDLE FOR KITCHEN UTENSILS OR SIMILAR ARTICLES

Myron J. Zimmer, Chicago, Ill., assignor to The Edward Katzinger Company, Chicago, Ill., a corporation of Illinois

Application October 21, 1939, Serial No. 87,791

Term of patent 14 years

To all whom it may concern:

Be it known that I, Myron J. Zimmer, a citizen of the United States, residing at Chicago, in the county of Cook and State of Illinois, have invented a new, original, and ornamental Design for a Handle for Kitchen Utensils or Similar Articles, of which the following is a specification, reference being had to the accompanying drawing, forming part thereof.

Fig. 1 is a side elevational view of a handle

for kitchen utensils or similar articles showing my design.

Fig. 2 is a transverse sectional view taken
along line 2—2 of Fig. 1.

Fig. 3 is a transverse sectional view taken
along line 3—3 of Fig. 1.

I claim:

The ornamental design for a handle for kitchen utensils or similar articles, as shown.

MYRON J. ZIMMER.
